BLOCK-SIGNAL SYSTEM.

1,085,981.

Specification of Letters Patent. Patented Feb. 3, 1914.

Application filed July 14, 1908. Serial No. 443,475.

To all whom it may concern:

Be it known that I, LAURENCE A. HAWKINS, a citizen of the United States, residing at Schenectady, county of Schenectady, 5 State of New York, have invented certain new and useful Improvements in Block-Signal Systems, of which the following is a specification.

My invention relates to block signal systems, and particularly to signal systems of the normal danger type.

The object of my invention is to provide an efficient and reliable system of this character having a minimum amount of apparatus and few line wires.

In a normal danger system employing home and distant signals, or their equivalent, to indicate danger, caution and clear, it is desirable that if the two blocks ahead 20 of a train are not occupied, the home signals for both blocks should be clear as well as the distant signal immediately ahead of the train and controlled by the home signal in advance. That is, three signals should 25 be cleared; the clearing of the distant signal depending upon the clearing of the home signal in advance and the clearing of the home signal in advance depending upon the clearing of the home signal immediately 30 ahead of the train. To obtain these operations in proper sequence with a minimum number of line wires, a number of systems have been proposed heretofore, many of 35 which involve the use of a large number of relays. By my invention I am enabled to reduce the number of line relays, that is, relays other than track relays, to two per block. I accomplish this by the use of 40 polarized relays and by certain novel connections.

One feature of my invention consists in a novel arrangement for reversing the current in a circuit to actuate a polarized relay therein. This arrangement consists in providing a source of voltage for first sending 45 a current through the circuit in one direction and then introducing in shunt to a portion of the circuit a second source of voltage higher than, and in opposition to, the first, so that the direction of the current is reversed without opening the circuit. Furthermore, by this means I am enabled to reverse the current in a line wire without reversing the current in a polarized relay connected to one end of the line wire and in

series with it. This will be further explained hereafter.

Another feature of my invention consists in a novel interconnection of the polarized relay and non-polarized or neutral relay. Where neutral and polarized relays have been connected in series and a reversal of current has been employed to actuate the polarized relays, it has heretofore been necessary to resort to special designs of the neutral relay in order to prevent it from dropping its armature while the current is reversed. I avoid the necessity of such special designs by arranging the front contacts of the polarized relay to shunt the front contacts of the neutral relay, so that it is only necessary that the neutral relay should be slow acting so that the polarized relay may close its front contacts, thereby shunting the front contacts of the neutral 75 relay, before the front contact of the neutral relay has time to reopen. The difference between slow acting and quick acting relays is well understood in the art, and to produce either action requires no unusual design.

Another feature of my invention, which enables me to reduce the number of relays, consists in providing certain relays with two windings, either of which is adapted to actuate the relay, and connecting those two windings in different circuits which are alternately but not simultaneously closed. The relay responds to each winding in turn as though the other winding was not present, and the same results are obtained with one relay thus arranged as with two ordinary relays.

My invention further comprises other features of novelty which will best be understood by reference to the accompanying drawings, in which—

Figure 1 shows diagrammatically in its preferred form a signal system arranged in accordance with my invention, while Fig. 2 100 shows a modification of the system.

Referring to Fig. 1, A, A¹ and A² represent the rails of three successive blocks of a block signal system, the direction of travel being as indicated by the arrow.

B¹ and B² represent the track batteries for blocks A¹ and A².

C, C¹ and C² represent the track relays for the three blocks. Each track relay has four contact fingers c to c³.

110

D¹, D² and D³ represent line relays which are nonpolarized and slow acting.

E¹, E² and E³ represent quick acting polarized relays. Each of these latter relays has two windings e and e¹ which are connected in different circuits and either of which when energized with current in the proper direction will operate the relay.

F¹, F² and F³ represent home signals, each of which is arranged to actuate a contact f. The connections between these signals and these contacts are indicated diagrammatically by dotted lines.

G¹, G² and G³ represent distant signals.

H¹, H² and H³ represent sources of current, indicated as batteries. In addition to its end terminals each battery has two intermediate terminals h and h¹. The four terminals are represented as equally spaced; one-third of the total number of cells in the battery being included between each pair of adjacent terminals.

I represents a return wire common to all signal circuits.

J¹ and J² represent line wires extending through blocks A¹ and A², respectively, each forming with the common return wire I and the relay winding connections a single normally open circuit for each block.

The parts of the system are shown in the positions they occupy when all the blocks are clear. All the circuits, except the track circuits, are open and all the signal apparatus, except the track relays, are deenergized. If a train is in block A, the track relay C is deenergized and drops its contact fingers. A circuit is thereby closed from intermediate terminal h of battery H² through the winding e of relay E², contact finger c

and front contact of relay C¹, line wire J¹, neutral relay D¹, contact finger c², and back contact of relay C, winding e¹ of relay E¹, common return wire I to terminal h¹ of battery H². One-third of battery H² is thus connected in series with polarized relays E¹ and E² and neutral relay D¹. The connections of the relay windings e and e¹ of each of the polarized relays are so shown in the drawing that if the upper terminals of the

batteries be considered positive, it may be assumed that current passing through the relay windings in the direction of traffic will energize the polarized relays, while current in the opposite direction will not affect them. Thus being the case it will be seen that relay E² is energized, while relay E¹ is not affected. Relay D¹ is, of course, energized. The shifting of the contact fingers of relays D¹ and E² results in clearing home

signals F¹ and F². The circuit for signal F¹ may be traced from the upper terminal of battery H¹, through the contact finger of relay D¹, through the operating mechanism of signal F¹, to the lower terminal of battery H¹. The home signal F¹ is consequently

cleared. The clearing of home signal F² is brought about in the following manner: Relay E² has been energized as above pointed out. The shifting of its contact fingers closes a circuit from the upper terminal of battery H², through the upper contact finger of relay E², front contact and contact finger c² of relay C¹, neutral relay D², line wire J², front contact and contact finger c of relay C² (block A² being unoccupied), winding e of polarized relay E³, terminal h of battery H³, through two cells of this battery to terminal h¹, line wire I to terminal h¹ of battery H². Four cells of battery H² are consequently thrown into circuit with, and in opposition to, two cells of battery H³, so that the direction of flow to line wire J² is in the opposite direction to the current flow in line wire J¹. Polarized relay E³ is consequently not energized. Neutral relay D² is however energized and closes a circuit through battery H² and the operating mechanism of home signal F². Home signal F² is, therefore, cleared and in clearing closes its contact f. This contact connects the lower terminal of battery H² with line wire J¹ through contacts c and c¹ of relay C¹. A branch circuit is therefore closed around winding e of relay E², which branch circuit includes the two lower cells of battery H². This branch circuit includes no resistance other than the resistance of the wires and contacts, but the other branch includes the resistance of winding e of relay E²; and since the two portions of battery H² included in these two branches are of equal potential, the current from the two lower cells will predominate in the main circuit. But this current flows in the direction reverse to that of the current from the cells between points h and h¹, hence the direction of flow of current through relay D¹ and winding e of relay E¹ is reversed and relay E¹ is therefore so energized as to close its front contacts. It will be noted that the direction of flow of current through winding e of relay E² remains unchanged hence this relay is unaffected.

Relay D¹ may drop its contact finger and pick it up again without opening the circuit of home signal F¹, provided the action of relay D¹ is slow enough to permit relay E¹ to close its contacts before relay D¹ opens its contacts. The reason for this is that the upper contact finger of relay E¹ is connected through contact finger c³ and back contact of relay C in shunt to the contacts of relay D¹, so that it forms a maintaining circuit for home signal F¹. At the same time the circuit of distant signal G¹ is closed as follows: from the upper terminal of battery H¹, through the lower contact fingers of relay E¹, to the operating mechanism of signal G¹, back contact and contact finger c¹ of relay C, contact f of F¹, to lower ter-

5 minal of battery H^1 . The distant signal G^1 is, therefore, cleared. Thus with a train in block A and blocks A^1 and A^2 unoccupied, home signals F^1 and F^2 and distant signal 10 G^1 are clear. When the train enters block A^1 , it short-circuits track relay C^1 and this relay at its contact c opens the circuit of relays E^1 and D^1 and puts signals F^1 and G^1 to danger. Home signal F^2 and distant 15 signal G^2 are then cleared as has already been described for signals F^2 and G^1 .

10 Fig. 2 shows a modification of the system. This modification in some respects is inferior to the arrangement of Fig. 1, since it necessitates a special construction of the neutral 15 relays such that they will not drop their contact fingers upon a quick reversal of current flow and also since it renders available for the first operation of the relays only 20 one-sixth of the total battery voltage instead of one-third as in Fig. 1. The modification, however, illustrates a further extension of the principle utilized in the system of Fig. 1 for reversing the direction of current 25 flow in the circuit, that is, inserting in the circuit a higher opposing voltage, and the special construction of the neutral relay is not a serious disadvantage, for such special constructions are now well known in the 30 art. (See, for instance, Patent No. 799,816, issued to H. E. White, September 19, 1905.)

35 In Fig. 2 as in Fig. 1 the parts are all shown in the positions they occupy when all the blocks are clear. A train entering block A would deenergize relay C and close a circuit from terminal h^1 of battery H^2 , through the back contacts of contact f on signal F^2 , through contact finger c of relay C^1 , winding e^1 of polarized relay E^2 , line wire J^1 , 40 neutral relay D^1 , winding e of polarized relay E^1 , contact fingers c^1 and c^2 and back contacts of relay C, upper finger and back contact of relay D^1 , common wire I, and the lowest terminal of battery H^2 . It will be 45 noted that the number of cells of each battery between adjacent terminals are, beginning at the bottom, one, two and three. One cell of battery H^2 is thus connected in series with relays E^2 , D^1 and E^1 . The direction 50 of current flow in both polarized relays is such as not to operate them. Neutral relay D^1 is, however, energized and its lower contact finger closes a circuit through battery H^1 and the operating mechanism of home 55 signal F^1 . Its upper contact finger in rising opens its back contact so that the current flowing through the relays E^1 and D^1 now passes to common return wire I through resistance k^1 , and when the contact finger 60 reaches its front contact it closes another circuit which may be traced as follows: from terminal h of battery H^1 , through the front contact and upper finger of neutral relay D^1 , back contacts and contact fingers 65 c^2 and c^1 of relay C, winding e of relay E^1 ,

neutral relay D^1 , line wire J^1 , winding e^1 of relay E^2 , front contact and finger c of relay C^1 , back contacts of contact f of signal F^2 , terminal h^1 of battery H^2 , through one cell of that battery and through line wire I to the lowest terminal of battery H^1 . Three 70 cells of battery H^1 are thus thrown in opposition to one cell of battery H^2 so that the direction of current flow through line wire J^1 and through relays E^1 , D^1 and E^2 is reversed. It will be noted that resistance k^1 75 is also connected across the three lower cells of battery H^1 ; this resistance being thrown into circuit to avoid short-circuiting of the battery. The reversal of current in relay D^1 as has been said does not cause this relay to open its contact, but this modification of this system is designed so as to stand a quick reversal of current without dropping its contact fingers. 80

85 Relays E^1 and E^2 are both operated by the current reversal. The operation of relay E^1 produces no useful effect. The operation of relay E^2 , however, results in clearing home signal F^2 provided block A^2 is unoccupied. 90 The circuit that produces this effect may be traced as follows: from the terminal h^1 of battery H^3 , through back contact f of signal F^3 , front contact and contact finger c of relay C^2 , winding e^1 of polarized relay E^3 , 95 line wire J^2 , neutral relay D^2 , front contact and contact finger c^1 of relay C^1 , lower contact of relay E^2 , resistance k^2 to common line wire I. One cell of battery H^3 is thus connected in series with relay E^3 , relay D^2 100 and resistance k^2 . Neutral relay D^2 consequently lifts its contact fingers, closing the circuit of the operating mechanism of signal F^2 . Its upper contact finger performs no function, since its circuit is open at back contact of contact finger c^2 of relay C^1 . When 105 signal F^2 clears, its contact f closes a new circuit which may be traced as follows: from the upper terminal of battery H^2 , contact f of signal F^2 , upper contact of polarized relay E^2 , contact finger c^3 of relay C to the connection between the front contact of that relay finger and line wire J^1 . Here the current divides, part passing through winding e^1 of relay E^2 and contact finger c 110 of relay C^1 , through resistance K^2 to terminal h^1 of battery H^2 so that relay winding e^1 and resistance K^2 are thrown in series across five cells of battery H^2 , the current flow of relay winding not being reversed. Resistance K^2 is inserted in circuit merely to reduce the flow of current and is not essential. 115 The other part of the current passes through line wire J^1 , neutral relay D^1 , winding e of polarized relay E^1 , contact finger c^1 of relay C, resistance k^1 , line wire I to the lowest terminal of battery H^2 . Six cells of battery H^2 are thus thrown into opposition to three cells of battery H^1 and the current through 120 relays D^1 and E^1 is, therefore, again 125 relays D^1 and E^1 is, therefore, again 130

versed, throwing relay E^1 back to its original position. Home signal F^1 has been cleared and a circuit is therefore closed from upper terminal of battery H^1 , contact f of signal F^1 , back contacts and upper contact finger of relay E^1 , operating mechanism of distant signal G^1 to lowest terminal of battery H^1 . Distant signal G^1 is therefore cleared.

10 When a train enters block A^1 , the circuit of winding e^1 of relay E^2 is opened at contact finger c of relay C^1 and the circuit of wire J^1 and the neutral relay D^1 is opened at the front contacts and upper contact fingers of relay E^2 and at contact finger c^3 of relay C^1 so that relay D^1 is deenergized, putting signal F^1 to danger, which in turn puts distant signal G^1 to danger by opening contact f .

15 Other modifications of my system will be obvious to those skilled in the art, and consequently I do not desire to limit myself to the particular connections and arrangement of parts here shown, but aim in the appended 20 claims to cover all modifications which are within the scope of my invention.

What I claim as new and desire to secure by Letters Patent of the United States, is—

1. In a block signal system, a line wire 30 extending through a block, a slow-acting neutral relay and a quick-acting polarized relay in circuit with said line wire, the polarized relay having front contacts connected in shunt to front contacts of the neutral relay, 35 means for sending current through said line wire in a direction to operate the neutral relay only, means for reversing the direction of current flow in said line wire, and signals adapted to indicate danger, caution and 40 clear controlled by said relays.

2. In a normal danger block signal system, a track relay for each block, a normally-open circuit for each block section each circuit including a line wire extending 45 through the block section and each circuit arranged to be closed when the track relay for that block is energized and the track relay for the preceding block is deenergized, a neutral relay winding and a polarized relay winding included in said circuit at the 50 entrance of the block, a polarized relay winding included in said circuit at the exit end, signals controlled by said relays, a source of current adapted, when said circuit 55 is closed, to send through it a current in a direction to energize the polarized relay at the exit end but not the other, means controlled by the polarized relay at the exit end for closing the circuit for the block in 60 advance and sending through it a current in opposition to the voltage of the source in that circuit, a branch around the polarized relay at the exit end of each circuit which branch includes a second source of current of opposite 65 polarity and means controlled by the sig-

nal for the block in advance for opening and closing said branch thereby reversing the flow of current in the circuit for the first-mentioned block but not in the polarized relay winding at its exit end.

3. In a normal danger block signal system, a track relay for each block, a normally-open circuit for each block section each circuit including a line wire extending through the block section and each circuit arranged to be closed when the track relay for that block is energized and the track relay for the preceding block is deenergized, a neutral relay winding and a polarized relay winding included in said circuit at the entrance of the block, a polarized relay winding included in said circuit at the exit end, signals controlled by said relays, a source of current in said circuit, means controlled by the polarized relay at the exit end for closing the circuit for the block in advance, a branch around the polarized relay at the exit end of each circuit which branch includes a second source of current of opposite polarity and means controlled by the signal for the block in advance for opening and closing said branch thereby reversing the flow of current in the circuit for the first-mentioned block but not in the polarized relay at the exit end.

4. In a railway signaling system, a plurality of block sections, a polarized line relay for each block section, sources of current of different voltage for each block section, a circuit for each block section extending through the section and including a winding of the polarized relay and one source of current for the block section next in advance, and a circuit controller included in each of said circuits for introducing into such circuit a winding of the polarized relay of the corresponding block section or a source of current of a different voltage for the corresponding block section according as the circuit controller is in one position 110 or another, and signals controlled by said polarized relays.

5. In a railway signaling system the combination of a plurality of block sections, a track relay for each block section, a polarized line relay for each block section, sources of current of two voltages for each block section, a circuit for each block section extending through the section and including a winding of the polarized relay and a source of current of one voltage for the block section next in advance, and a circuit controller in each circuit and included in the track relay for the corresponding block section for introducing into said circuit a winding of the polarized relay of the corresponding block section or the source of current of the other voltage for the said corresponding block section according as the circuit controller is in one position or an- 130

other, and signals controlled by said polarized relays.

6. In a railway signaling system the combination of a plurality of block sections, a track relay for each block section, a polarized line relay for each block section, sources of current of two voltages for each block section, a circuit for each block section extending through the section and including a winding of the polarized relay and a source of current of one voltage for the block section next in advance, and a circuit controller in each circuit and included in the track relay for the corresponding block section for introducing into such circuit a winding of the polarized relay of the corresponding block section or the source of current of the other voltage for the said corresponding block section according as the circuit controller is in one position or another, and a circuit controller operated by each track relay and included in the circuit for the corresponding block section, and signals controlled by said polarized relays.

7. In a railway signaling system the combination of a plurality of block sections, a track relay for each block section, a polarized line relay and a neutral line relay for each block section, sources of current of two voltages for each block section, a circuit for each block section extending through the section and including a winding of the polarized relay and a source of current of one voltage for the block section next in advance and the winding of the neutral relay for the corresponding block section, a circuit controller included in each circuit and operated by the track relay for the corresponding block section for introducing into such circuit a winding of the polarized relay of the said corresponding block section or the source of current of the other voltage for the corresponding block section according as the circuit controller is in one position or another, and signals controlled by the said line relays.

8. In a railway signaling system the combination of a plurality of block sections, a track relay for each block section, a polarized line relay for each block section, sources of current of two voltages for each block section, a circuit for each block section extending through the section and including a winding of the polarized relay and a source of current of one voltage for the block section next in advance, a circuit controller included in each circuit and operated by the track relay for the corresponding block section for introducing into such circuit a winding of the polarized relay of the corresponding block section or the source of current of the other voltage for the said corresponding block section according as said circuit controller is in one position or another, a circuit controller operated by each polarized

relay and included in the circuit for the corresponding block section for controlling said circuit when said circuit includes the second-mentioned source of current, and signals controlled by said polarized relays.

9. In a railway signaling system, the combination of a plurality of block sections, a track relay for each block section, a neutral line relay and a polarized line relay for each block section each polarized relay having two windings, sources of current of two voltages for each block section; a circuit for each block section extending through the section and including a source of current of one voltage and a winding of the polarized relay for the block section next in advance and the winding of the neutral relay for the corresponding block section, and a circuit controller included in each circuit and operated by the track relay for the corresponding block section for introducing into such circuit the other winding of the polarized relay for the corresponding block section or the source of current of the other voltage for such corresponding block section according as the circuit controller is in one position or another, and signals controlled by the said line relays.

10. In a railway signaling system the combination of a plurality of block sections, a track relay for each block section, a polarized line relay for each block section each having two windings, sources of current of two voltages for each block section, a circuit for each block section extending through the section and including a source of current of one voltage and a winding of the polarized relay for the section next in advance, and a circuit controller included in each circuit and operated by the track relay for the corresponding block section for introducing into such circuit the other winding of the polarized relay for the corresponding block section or the source of current of the other voltage for such corresponding block section according as the circuit controller is in one position or another, and signals controlled by the said line relays.

11. In a railway signaling system the combination of a plurality of block sections, a polarized line relay for each block section each having two windings, sources of current of substantially equal potential but opposite polarity for each block section; a circuit for each block section each including one source of current and a winding of the polarized relay at the exit end of the block section, and the other winding of the polarized relay at the entrance of the block section; a branch circuit around the first mentioned one source of current and a winding of the polarized relay at the exit end of the section which branch includes the other adjacent source of current, and means for controlling said branch circuit whereby the direction of flow of current through

the winding of the polarized relay at the entrance end of the block section may be reversed.

12. In a railway signaling system the combination of a plurality of block sections, a polarized line relay for each block section each having two windings, sources of current of substantially equal potential but opposite polarity for each block section; a circuit for each block section each including one source of current and a winding of the polarized relay at the exit end of the block section, and the other winding of the polarized relay at the entrance end of the block section; 10 a branch around the first mentioned winding of the polarized relay at the exit end, which branch includes the other adjacent source of current, a home signal for each block section, means included in the said circuits for 15 controlling said signals, a circuit controller operatively connected with each home signal and included in the said branch for the circuit of the block section next in rear of said home signal for controlling said branch 20 whereby the direction of flow of current in the polarized relay at the entrance end of the block section may be reversed, and a dis- 25

tant signal controlled by each polarized relay.

13. In a railway signaling system a plurality of block sections, a polarized line relay for each block section each having two windings, sources of current of substantially equal potential and opposite polarity for each block section; a circuit for each block section each comprising one source of current and a winding of the relay at the exit end of the block section, and the other winding of the relay at the entrance end of the block section; a branch around the first- 30 mentioned winding of the relay at the exit end each branch including the other adjacent source of current, and means for controlling each branch whereby the direction of flow of current through the winding of the relay at the entrance end of the block section may be reversed. 35

In witness whereof, I have hereunto set my hand this 13th day of July, 1908.
